[57] **CLAIM**

The ornamental design for a shirt, as shown and described.

DESCRIPTION

FIG. 1 is a perspective view of a shirt showing my new design; the broken line showing the human form being for illustrative purposes only;

FIG. 2 is an enlarged front elevational view thereof;

FIG. 3 is an enlarged rear elevational view thereof;

FIG. 4 is an enlarged side elevational view thereof, both sides being substantially identical;

FIG. 5 is an enlarged top plan view thereof;

FIG. 6 is an enlarged bottom plan view thereof.
